UNITED STATES PATENT OFFICE.

CHARLES J. KERN, OF BUFFALO, NEW YORK, ASSIGNOR TO NEW ERA TOY MANUFACTURING COMPANY, INC., OF CHERRY CREEK, NEW YORK, A CORPORATION OF NEW YORK.

TOY AERIAL SWING.

1,379,575.

Specification of Letters Patent. Patented May 24, 1921.

Application filed April 24, 1919. Serial No. 292,268.

To all whom it may concern:

Be it known that I, CHARLES J. KERN, a citizen of the United States, residing at Buffalo, in the county of Erie and State of New York, have invented certain new and useful Improvements in Toy Aerial Swings, of which the following is a specification.

My invention relates to a toy, and more particularly to a toy aerial swing.

- 10 One of the objects of my invention is the provision of a toy of this character, which can be folded within a compact space so that it can be easily stored when not in use, or when not on display.
- 15 A further object of my invention is the production of a toy of this kind in which the swinging boxes or "cars", as they may be termed, are removable from their supporting arms, but in which all other parts 20 of the toy remain in connected condition but are foldable or contractible so as to occupy a comparatively small space.

- 25 Another object of my invention is the provision of a folding toy of this kind in which the suspended or swinging boxes or cars may be arranged within or around certain elements of the device when folded, in such a manner that the entire space occupied by the device is no greater than would be occupied 30 without the boxes or cars.

- 35 Further objects are the provision of novel means for connecting the various parts of the toy, the provision of novel means for driving or operating the same, and the provision of a folding base, one part of which carries the driving element of the toy.

- With these and other objects in view, the invention consists in the novel features of construction and in the arrangement and 40 combination of parts to be hereinafter described and more particularly pointed out in the subjoined claims.

In the drawings:—

- 45 Figure 1 is a perspective view of my improved toy showing the parts thereof unfolded or extended ready for operation.

Fig. 2 is a central longitudinal section through the device.

- 50 Fig. 3 is a side elevation of the device in folded condition, with the swinging boxes or cars arranged within or around folded parts.

Fig. 4 is a vertical section taken on line 4—4, Fig. 3.

Fig. 5 is a perspective view of the device in folded condition, with the boxes or cars 55 removed therefrom.

Having reference now to the drawings in detail, like numerals refer to like parts in the several figures.

The reference numeral 6 designates a base, 60 7 a rotatable upright or mast stepped into the base and to the upper end of which a head or disk 8 is secured. Radiating from said head or disk are supporting arms 9, six in number being shown on the drawings and 65 spaced equi-distantly around the head or disk.

The base is substantially cross shaped in formation and comprises a longitudinal member 10 having two parts 11, 12 hinged 70 together, as at 13, and a cross member 14 joined to said longitudinal member in any approved manner and extending equal distances from opposite sides thereof. In the construction of the base I employ what is 75 generally known as a half check joint; that is, the part 12 of the longitudinal member and the cross member 14 are notched so that the thickness of each of these parts at the notch is one-half that of the parts at any 80 other point, and the reduced portion of each part fits into the notch of the other part so that a flush upper surface is provided where the two parts of the base cross each other. At this half check joint a bearing block 15 85 is arranged, which covers the joint and strengthens the base at this point. Arranged within this bearing block is a step bearing 16 into which a trunnion 17 extending from the lower end of the rotatable upright or 90 mast is journaled.

Surrounding the rotatable upright a distance beneath the head or disk 8 is a block 18, and extending from this block to the outer ends of the cross member 14 and also to the 95 outer or, what may be termed, rear end of the longitudinal member are braces 19. These braces serve to hold the rotatable upright in vertical position, and the block 18 also serves as a bearing for said upright. 100 The base 6, block 18 and braces 19 constitute what may be termed the frame of the device.

I preferably secure the head or disk 8 to the upper end of the rotatable upright or mast by means of a screw 20 passing axially 105 through said head or disk and taking into

said upright. The head or disk is notched around its marginal portion, as at 21, to receive the inner ends of the arms 9, suitable eyes 22 being fastened into the peripheral face of said head or disk at opposite sides of each notch, and fastened into each arm so as to project from opposite sides thereof is a pivot pin 23 which is passed through the eyes at opposite sides of the notch in which the inner end of said arm is fitted. While this is the preferred construction, I wish it to be understood that within the broader scope of my invention, any other manner of pivoting the arms 9 to the head may be resorted to, but the arrangement herein shown and particularly described, is exceedingly simple, very cheap and easily constructed.

With the pivot of the arms or sweeps 20 close to the inner extremities of the same, these arms tend to swing downwardly on their pivots and therefore when extended or arranged in horizontal position, some provision must be made to retain them in such position. For this purpose I preferably employ turn buttons 24 which are fastened to the upper face of the head or disk 8 by means of screws 25, one end of each turn button being adapted to be moved over one 25 of the notches 21 in said head or disk so that when the arms 9 are swung upwardly into horizontal position, the turn buttons may be engaged with the upper edges of said arms at their inner ends to hold them securely in position. When it is desired to swing the arms downwardly into the positions shown in Figs. 3 to 5, the turn buttons 24 are turned on the screws which fasten them in place, until they are moved out 30 of line with the notches in said head or disk, whereupon the arms 6 drop into lowered position.

26 designates boxes or, what may be termed "aerial cars" which are suspended 45 from the outer ends of the arms 9 and into which small dolls may be seated to give the device a realistic appearance. Each box or car is positioned in a plane between two arms, and is suspended from the two arms, 50 and for this purpose each box has cords or chains 27 extending upwardly from each end, which cords or chains are detachably fastened to the arms 9 in any approved manner. Preferably, each arm has hooks 28 55 extending from opposite sides thereof near its outer end, and the chains or cords are suspended from these hooks.

Pivots secured to one of the parts of the longitudinal member 10 of the base, 60 shown in the drawing as part 12, is a retainer member 29 which is pivotally secured to the part 12 by a screw 30, one end of said retainer member extending over the inner or pivoted end of the part 11 of said longitudinal member so as to prevent said

part 11 swinging upwardly on the part 12. This retainer member therefore serves to keep the two parts 11, 12 of said longitudinal member in alinement and converts the longitudinal member 10 into what may be 70 termed a "rigid unitary structure."

This toy will be painted to make the same attractive and in order to avoid scratching of the paint at the jointed portion of the longitudinal member, I fasten to the two 75 parts of said member at opposite sides of the joint, metal staples 31, against which the pivoted retainer member 29 is adapted to contact. In this manner said retainer member is prevented from rubbing in contact 80 with the painted upper surface of the base.

Fastened to the outer end of the part 11 of said longitudinal member are two brackets 32 between which a chain or cable sheave 33 is located, said sheave having suitable 85 journals 34 for which said brackets serve as bearings, and to one of said journals a crank arm 35 is secured, said crank arm having a handle 36 by means of which the chain or cable sheave or "driving member," as it may 90 be termed, may be rotated.

Secured to the rotatable upright or mast near its lower end is a chain or cable sheave 37 and around the same and the sheave or driving member 33, a chain or other flexible driving element 38 is passed so that when rotating said driving element, the upright or mast of the device is caused to rotate, carrying with it the arms 9 and the boxes or cars 26 suspended from said 100 arms. During rotation, these boxes or cars are caused to travel a circular path and are moved outwardly by centrifugal force, depending on the speed at which the upright or mast is rotated.

To further stiffen the frame work of the construction, a metallic band 39 is arranged 105 on the base so that it overlies the two members of the same at four sides of the bearing block 15. In this manner the two parts 110 of the base are stiffened against relative movement in a horizontal plane and wabbling of the braces 19 is also prevented. Said metallic band 39 is preferably formed of wire and secured to the base at four 115 points by means of staples 40. This band also serves as a support for some of the boxes or cars when the device is folded, as will be explained hereinafter.

While I have referred to the suspending 120 chains of the boxes or cars in a general way only, I prefer to employ two lengths of chains at each end of a box or car, the lower ends of said two lengths being fastened to the car in any suitable manner near opposite sides thereof and the upper ends being connected together by means of an eye 41 so that the chains converge upwardly and are connected together by said eye. The eyes 41 serve as means which will permit 130

the ready attachment of the upper ends of the chains to the hooks 28 extending from opposite sides of the arms 9.

The device with its parts in operative 5 or unfolded position appears as shown in Figs. 1 and 2, and when it is desired to fold the same, the boxes or cars are removed by unhooking the eyes 41 of the chains attached to the cars from the hooks 28 of 10 the arms. The pivoted retainer member 29 is then turned on its pivot so as to position the same as shown in Fig. 5, after which the part 11 of the longitudinal base member may be swung upwardly into the position 15 shown in Figs. 3 and 5. This will cause the chain or flexible driving element 38 to become disengaged from the sheave 37 on the rotatable mast, as shown in Figs. 3 and 5. The turn buttons 24 are then 20 rotated, which permits the arms 9 to swing downwardly to the positions shown in Figs. 3 to 5. The main structure of the device is then completely folded. The six boxes or cars may now be arranged around or 25 between different parts of the device while in folded position. This is done by arranging two boxes in rear of the braces 19 attached to the cross member 14, as shown in Figs. 3 and 4, said boxes being supported 30 on the portions of the metallic band 39 extending from the braced end of the longitudinal member 10 of the base to the cross member 14, with two arms 9 resting against said boxes, as indicated at 42, Fig. 3. Said 35 two boxes are preferably set on end. In the space between the braces extending upwardly from the cross member and the outer pivoted part 11 of the longitudinal member 3, three boxes or cars are positioned, two of said boxes being supported 40 on their sides and resting upon the remaining portion of said metallic band; that is to say, that portion of the band extending forwardly or toward the pivoted part of 45 the longitudinal base member, and the third box or car being arranged upon one of the two last-mentioned boxes or cars. The sixth or last box or car is arranged in practically inverted position over the upper end 50 of two of the sweeps or arms, as shown in Fig. 3, with one side of the box receiving support from the upper or outer end of the pivoted part 11 of the longitudinal base member. Therefore, when the device is 55 folded and the boxes or cars are arranged within or around the certain parts of the device, it has the appearance shown in Fig. 3. With the boxes so arranged, the device occupies no more floor space than would 60 be required if the main structure of the device were folded and no boxes or cars were used. The advantages of this device are therefore quite apparent, particularly since in a toy of this kind, considerable 65 floor space will be required when it is in

use, and when folded it occupies only a fraction of the space required when the parts are extended or unfolded.

Having thus described my invention, 70 what I claim as new is:—

1. A device of the kind described, comprising a foldable base, a vertical mast having its lower end journaled in said base, means for supporting said mast at a point spaced from said base, a driving element 75 mounted on the foldable part of said base, transmission means between said driving element and said mast, arms extending outwardly at the upper end of said mast, and aerial elements suspended from said arms. 80

2. In a device of the kind described, a rotatable vertical member, a disk at the upper end of said vertical member having peripheral notches therein, arms pivoted to said disk and having their inner ends within 85 said notches, and turn buttons on said disk engaging the upper edges of said arms at their inner ends to hold said arms in extended and horizontal position, said arms or sweeps being adapted to swing downwardly when said turn buttons are disengaged therefrom. 90

3. A device of the kind described, comprising a base having a longitudinal member formed of two parts hinged together 95 and a cross member connected to said longitudinal member and extending from opposite sides thereof, a mast having its lower end journaled in said base at one part of said longitudinal member, a driving element 100 secured to the other part of said longitudinal member, flexible transmission mechanism between said driving element and said mast, arms extending outwardly from the upper end of said mast, boxes suspended from said 105 arms, and means for preventing one part of said longitudinal member from swinging on the other part thereof. 110

4. An aerial swing including a rotatable mast, a base on which said mast is mounted, 115 said base including a hinged part, a driving element on said hinged part, a transmission element between said driving element and said mast, and means for holding said hinged part in line with the other part of said base.

5. An aerial swing including a base and a rotatable member mounted on said base, said base including two hinged parts on one of which said member is supported, a sheave 120 journaled on the other part of said base, a sheave on said rotatable member, a flexible driving element passing around said sheaves, and means to retain the hinged parts of said base in alinement. 125

6. In an aerial swing, a base comprising two parts, a mast journaled at its lower end in one of said parts, a bearing near the upper end of said mast, arms extending outwardly from the upper end of said mast, 130

aerial elements suspended from said arms, a driving element mounted on one part of said base, driving mechanism between said driving element and said mast, and means 5 permitting the part of said base having said driving element thereon to be swung upwardly and inwardly toward said mast.

7. In a device of the kind described, a base having two parts hinged together, metallic contact elements on the two parts of 10 said base at opposite sides of the hinged connection thereof, a pivoted retainer secured to one of said parts and adapted to bear against said metallic contact elements to 15 keep the two parts of said base in alignment, a rotatable structure mounted on one part of said base, a driving element mounted on the other part of said base, and a flexible transmission element between said

driving element and said rotatable structure, 20 the whole being arranged to permit one part of said base to swing on the other part thereof.

8. In a device of the kind described, a frame having a foldable base, a mast rotatable within said frame, arms extending outwardly from the upper end of said mast in horizontal positions, and box-like elements suspended from the outer ends of 25 said arms and detachably connected thereto, 30 said arms or sweeps being pivotally connected to the upper end of said mast so as to permit the same to swing downwardly and said box-like elements being adapted to be positioned between parts of said device 35 when folded.

In testimony whereof I affix my signature.

CHARLES J. KERN,
